(57) **CLAIM**

The ornamental design for a sit-stand workstation, as shown
and described.

DESCRIPTION

FIG. 1 is a perspective view of a sit-stand workstation
showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a perspective view thereof, shown in an alternate
position.

The dashed broken lines shown in FIGS. 1-7 illustrate
unclaimed portions of the sit-stand workstation. The bottom
view is omitted and forms no part of the claimed design.

1 Claim, 7 Drawing Sheets
